CONCEALED DOOR HINGE

Walter C. Wagner, Oneida, N. Y., assignor of fifty-one per cent to Lynn E. Johnson, Canastota, N. Y., J. Kenneth Johnson, Oneida, N. Y., and Burr Shaver, Cazenovia, N. Y.

Application May 23, 1935, Serial No. 23,081

2 Claims. (Cl. 16—129)

This invention relates to a door hinge, the general object of the invention being to so construct and arrange the hinge that it is hidden from view, with means whereby the hinge can be adjusted to 5 align the door.

This invention also consists in certain other features of construction and in the combination and arrangement of several parts, to be herein-after fully described, illustrated in the accompanying drawing and specifically pointed out in 10 the appended claims.

In describing the invention in detail, reference will be had to the accompanying drawing wherein like characters denote like or corresponding parts throughout the several views, and in 15 which:—

Figure 1 is a transverse sectional view through a portion of a door and a door frame showing the invention in use with a door and frame constructed of metal.

Figure 2 is a similar view but showing the door in open position.

Figure 3 is a view of the section of the hinge which is connected to the frame of the door.

Figure 4 is a view of the opposite hinge.

As shown in the drawing the numeral 1 indicates a flat leaf of a hinge which is to be connected to a post 2 on the frame and the numeral 3 indicates a substantially U-shaped leaf which has 30 its outer limb adapted to be connected to the recess part 4 of the post or pillar 5 of the door A. The other limb of the U-shaped part curves outwardly and is formed with a knuckle part 6 through which the hinge pin 7 passes, the pin also passes through the knuckles 8 of the leaf 1, the knuckle 6 fitting between the knuckles 8. A projection 9 is formed on the knuckle 6 for engaging a part of the leaf 1 to limit opening movement of the door as shown in Figure 2. A screw 10 passes 35 through a countersunk hole in the knuckle carrying limb of the leaf 3 with its head countersunk in said hole and said screw passes into a threaded opening in the other limb and lock nuts 11 are threaded on the screw and engage the adjacent faces of the two limbs as shown. This screw strengthens the U-shaped leaf 3 and pro-

vides means whereby the hinge can be adjusted to align a door.

When the hinge is positioned as shown in Figures 1 and 2 it will occupy the recess B formed between the posts 2 and 5 when the door is closed 5 so that the hinge will be hidden from view as shown in Figure 1. The post 2 is formed with the recessed part 2' for receiving the knuckles of the hinge and reinforcing plates 12 are placed on the inner faces of the outer parts of the post 10 to receive the screws fastening the leaves to the parts as shown in Figures 1 and 2. However, if the hinge is to be used on a wooden construction the outer limb can be extended at the side as shown at 13 in Figure 4 in dotted lines and the 15 screws pass through these extensions. This will enable large screws to be used for fastening the U-shaped leaf to the door, it being understood that when the outer limb of the U-shaped leaf is of the same width as the other limb and small 20 screws must be used and such screws are to be placed in threaded holes through the space between the limbs.

It is thought from the foregoing description that the advantages and novel features of the invention will be readily apparent.

It is to be understood that changes may be made in the construction and in the combination and arrangement of the several parts, provided that such changes fall within the scope of the 30 appended claims.

What is claimed is:—

1. A concealed hinge comprising a flat leaf, a U-shaped leaf having an end of one limb hingedly connected to the first leaf, and means 35 passing through the two limbs of the U-shaped leaf for reinforcing said leaf and for adjusting the distance between the two limbs.

2. A concealed hinge comprising a flat leaf, a U-shaped leaf having an end of one limb hinged- 40 ly connected to the first leaf, the other limb being adapted to be connected to a door, and a screw passing through the two limbs for reinforcing the limbs and for aligning the door.
